H. R. DAVIES

IGNITION SYSTEM

Filed Feb. 21, 1921

UNITED STATES PATENT OFFICE.

HENRY R. DAVIES, OF TOLEDO, OHIO, ASSIGNOR TO INDUSTRIAL RESEARCH CORPORATION, OF TOLEDO, OHIO, A CORPORATION OF DELAWARE.

IGNITION SYSTEM.

Application filed February 21, 1921. Serial No. 446,625.

To all whom it may concern:

Be it known that I, HENRY R. DAVIES, a citizen of the United States, residing at Toledo, county of Lucas, and State of Ohio, have invented certain new and useful Improvements in Ignition Systems, of which I declare the following to be a full, clear, and exact description.

This invention relates to ignition systems for engines and has particular application to the non-selfstarting type of internal combustion engines.

The invention has for an object the provision of means for generating current of approximately maximum pressure during the starting period of the engine.

A further object contemplated is the provision of means for increasing the energy of the ignition circuit at engine starting which shall be entirely automatic in its action.

Another object also is to establish a full automatic speed adjusting ignition system wherein the employment of movable or vibrating elements are rendered unnecessary.

An important object is to provide a system wherein the starting voltage is approximately maximum and which decreases in a more or less uniform rate as the speed increases to an average value most efficient for the normal running speed of the engine.

The invention further includes means for automatically decreasing the gradient of normal decrease of the voltage of the system as the speed increases; and novel switch mechanism for effecting simultaneous closure of the ignition and motor circuits while permitting singular operations of those circuits at opening.

Further objects, and objects relating to economies of manufacture and details of construction will become apparent as I proceed with the description of the various embodiments of my invention, which may be preferred, illustrated in the accompanying drawings, in which—

Figure I is illustrative of the invention applied to a single unit dynamo-electric machine normally operative either as a motor or a generator;

Figure II shows the invention applied to a two unit electric charging and engine

starting circuit wherein a separate motor and separate generator is employed, and;

Figure III illustrates a modification of the arrangement of Figure II.

Referring to Figure I there is shown a storage battery 10, which is designed to furnish current when the engine is not running, for starting and lighting purposes. Connected to the battery by means of main circuits 11 and 12, through the manual switch 13, is a dynamo-electric machine 14, the field 15 of which is connected in shunt around the dynamo-electric machine or starting generating dynamo, as it may hereinafter be designated, adjacent the main brushes 16 and 17.

The starting generating dynamo is illustrated as mounted on a shaft 18 which is operatively connected to an internal combustion engine (not shown). The starting generating dynamo is designed to transmit power as a motor through the shaft 18 to start the engine and thereafter to receive power from the engine as generator for charging and lighting purposes. To obtain these ends the storage battery is floated across the starting generating dynamo mains as described above and possesses a voltage approximately equal to the electric machine.

The ignition system shown is of the high tension type though any other type of ignition would be equally usable in connection with the invention. The primary circuit is illustrated as containing the primary induction coil 19, interrupter contacts 20 and 21, interrupter arm 22, and condenser 23 around the contacts 20 and 21.

One terminal 24 of the induction primary is connected through a switch 25 to the main brush 16. The other terminal 26 is connected through the interrupter and condenser to an auxilliary brush 27 which is operatively positioned on the starting generating dynamo armature between the main brushes.

The secondary circuit of the ignition system includes a high tension induction coil 28 connected to ground 29 at one end and connected at the other end through the distributing device 30 with its distributor arm 31 and spark plug circuits 32, to ground

33. The distributor is connected mechanically to the engine power shaft through the shaft 34, which also operates the interrupter cam 35 to open the interrupter contacts against the resilient pressure of spring 36, which latter bears on the interrupter arm 22.

It should be understood that the showing of the system throughout is diagrammatical. The starting generating dynamo is illustrated as a bipolar machine and merely the commutator is revealed but the various magnetic circuits, pole pieces and armature windings are conventional and are here omitted. Further a four pole machine would function as readily in connection with the invention as the 2 pole machine represented. The secondary circuit is shown as disconnected from the primary and a four cylinder sparking circuit indicated; but my invention applies as readily to a secondary connected to the primary at 24 and then to ground rather than a direct ground, and any number of sparking circuits might be employed.

In the consideration of the operation of the embodiment of the invention above described the various circuits and switches may be assumed to be initially as illustrated in Figure I with the starting generating dynamo and engine in a state of rest. While in this state the lights 37 or any other miscellaneous load may be supplied, through circuit 38 and switch 39, with energy from the storage battery.

To start the engine the switches 25 and 13 are closed. These switches may be closed simultaneously as more clearly brought out in the modified forms of my invention hereinafter described, or successively, in which latter case preferably the ignition switch 25 should be first closed.

With switches 25 and 13 closed, current from the battery passes into the starting generating dynamo circuits causing rotation of the armature in the direction indicated by the arrow. It is a well known characteristic of dynamo-electric machines that when operated as a motor the axis of commutation is shifted behind the neutral axis and when operated as a generator the axis of commutation is shifted ahead, for a given direction of rotation. Since this distortion is due to the magnetic interaction of armature and field it is evident that for the shunt machine considered the maximum angle of lead or lag of the commutation axis occurs for approximately maximum values of current, namely, when the motor is starting under load, or where the generator for a given load is rotating at highest speed.

Assuming that the main brushes 16 and 17 are fixed near the neutral axis it is evident that for the direction of rotation indicated and for appropriate values and direc-

tion of field flux and current there will be a maximum value of voltage between the brush 16 and auxiliary brush 27 at starting which voltage will progressively decrease as the starting generating dynamo begins to generate current and its load current increases. On the other hand as the load current in the generating starting generating dynamo decreases the voltage between brushes 27 and 16 increases.

The characteristics above described are utilized by connecting the ignition circuit to the auxiliary brush 27 and main brush 16 as previously indicated. This results in the highly advantageous effect of obtaining maximum voltage in the ignition circuit at starting when fuel condensation effects in the engine are most disadvantageous and carburetion relatively inefficient.

In my Patent Number 1,372,650 patented March 22, 1921, I have illustrated the application of the broad features of this invention to a starting generating dynamo wherein both the field and ignition are connected to an auxiliary brush and a main brush, between which the voltage decreases with speed thus securing a relatively rapid cumulative decrease of voltage in the ignition circuit. This arrangement is particularly advantageous in automotive traction units which are subject to continuous variation of speed; but for some uses particularly as applied to stationary units, I have found the arrangement as illustrated in Figure I with the shunt field connected directly across the main brushes, to be more advantageous, since the gradient depends almost directly on the armature reaction variable. This gives a more uniform and less rapid decrease of voltage during the generating period of the starting generating dynamo without in any way impairing the efficiency of the machine at starting.

In Figure II I have illustrated a modification of my invention as applied to a two unit system, wherein two dynamo electric machines, one normally functioning, as a generator and the other as a motor, are used.

The battery 10 supplies the lights 37 through circuit 38 and switch 39 as in the previously described arrangement.

Any type of suitable starting motor may be utilized but I have illustrated for the purposes of this invention a bipolar series type motor 50 mounted on a drive shaft 51 operatively connected with the engine to be started. One main brush 52 is connected through the field 53 to one battery terminal 54 and the other main brush 55 is connected through the switch 56 to the battery terminal 57.

The generator 58 is shown as a bipolar shunt machine mounted on an engine connected shaft 59. There are two main brushes 60 and 61 and an auxiliary brush 62 and the

shunt field 88 is connected to the auxiliary brush 62 and the main brush 60.

The generator is connected in parallel with the motor to the battery, the brush 61 having a closed circuit with battery terminal 54, and the main brush 60 is in circuit with the battery terminal 57 through a plurality of switches.

One of these switches, broadly indicated as 10 63, is automatic in operation being adapted for closure by the magnetic action of a shunt coil 64, on a movable armature contact arm 65, which arm carries a contact 66 registering with a corresponding stationary contact 15 67 in the generator circuit. The arm 65 has permanent electrical connection with a coil 68 also magnetically related to the contact armature 65 and in series with the main circuit from the generator brush 60 to the battery terminal 57.

The function of this switch 63 is to close the contacts 66 and 67 when the voltage of the generator has acquired a predetermined value suitable for charging the battery 10 and to open the contacts 66 and 67 when the generator voltage has decreased to a point where the combined magnetic effects of both shunt coil 64 and series coil 68 fails to maintain closure against the retractive action of 25 spring 69, an arrangement preventing contact chattering.

The switch 70 has a manual contact arm 71 adapted to effect closure of the main generator circuit and also of the ignition circuit as will be hereinafter set forth. The arm 71 is designed to move freely in a slot 72 cut in an operating handle 73 fixed to the motor switch arm 56. A spring 74 tends to maintain the switch 56 in a normal open 40 position as indicated in the drawing and in this position switch 71 may be either opened or closed because of the slotted connection to the handle 73. However with both switches in open position as illustrated closure of switch 56 will also simultaneously cause closure of switch 71 which dual closure will remain effective until pressure on the handle 73 is removed, when the switch 56 opens leaving the switch 71 closed. Subsequently 45 the switch 71 may be opened either by a continued upward movement of the handle 73 or by direct manipulation of the switch arm.

The ignition unit is similar in all respects to that described in connection with Figure I. 55 The primary circuit includes the primary induction coil 75, contacts 76 and 77, contact arm 78, spring 79 and condenser 80. The secondary circuit includes the grounds 81 and 82 secondary coil 83, distributor arm 84 and spark plug circuit contacts 85. The shaft 86 operates the interrupter cam 87 and the distributor arm 84.

One terminal of the ignition circuit is connected to the auxiliary brush 62 and the other terminal is connected to the main bat-

tery circuit between the switches 63 and 70. When the switch 63 is closed, therefore, both the generator field 88 and ignition are connected in parallel to the same brushes and subjected to the same armature reactive effects.

In describing the operation of the system illustrated in Figure II it may be assumed that the engine is at rest and the various switches in the positions as shown. Compressing the switch 70 closes the motor circuit and a circuit from the battery terminal 57 through the switch arm 71 primary ignition circuit, brush 62, armature windings and brush 61 back to battery terminal 54. Thereupon the ignition devices and motor are energized and the engine starts up under its own power.

As the engine speeds up the directly connected generator builds up a voltage which 85 closes the switch 63 at approximately the battery voltage. Current then passes from the generator through the switches 63 and 70 to the battery and charging of the same begins. Simultaneously on the closing of the 90 switch 63, ignition current is supplied the ignition system from the generator.

The particular features of the arrangement of Figure II are that current for ignition is initially supplied at battery voltage 95 and with no armature reactive effects, but that as soon as the generator functions, which is very shortly after the engine is started, a cumulatively varying voltage gradient dependent on at least two variables 100 is present. One of these variables is the main line voltage which is diminished with increase of speeds because of armature reaction, thereby affecting the voltage of the ignition circuit. The second variable is the 105 generator voltage on the ignition circuit which diminishes with increase of generator or engine speed or with increase of load as indicated with reference to Figure I. These factors combine to produce a relatively rapid 110 voltage drop characteristic on the ignition circuit, subsequent to closure of the automatic switch.

The arrangement of Figure II has been found particularly advantageous when used 115 in connection with small capacity batteries subject to more or less continuous charging conditions such as occur in automotive vehicle or railway cars. Under high speed conditions charging proceeds at a minimum 120 rate and may in fact entirely cease the automatic switch breaking the circuit. Similarly at low speeds the switch 63 automatically opens. But between the extremes of speed, the switch 63 is closed and the generator 125 furnishing ignition and charging current, the charging current being of course most effective at the lower speed ranges. In this way overcharging of the battery is prevented.

In the modification of Figure III the same units and circuits are utilized as shown in Figure II with the addition, however, of a resistance coil 90 in the primary ignition circuit.

The object of the resistance 90 resides in the necessity in some instances of providing in a system such as illustrated in Figure II means for diminishing the ignition voltage in the lower generator speed ranges without at the same time correspondingly decreasing the ignition voltages at the higher speed ranges to an inefficient value. A resistance coil with a high temperature coefficient such as iron has if properly designed relatively high resistance for large current but small resistance for small currents; and the use of such a device tends to flatten out the ignition voltage curve at lower speed ranges without diminishing the effectiveness of the high speed ignition and armature reactive influences described in reference to Figure II.

I am aware that the specific embodiment of my invention herein described and illustrated are subject to variation without departing from the spirit of the invention, and, therefore, I desire to claim the same broadly as well as specifically as indicated by the appended claims.

I desire to claim as my invention:

1. In an ignition system for gas engines, the combination of a dynamo-electric machine having main brushes and an auxiliary brush; a shunt field connected to the main brushes; an ignition circuit connected to the auxiliary brush and one of the main brushes; a storage battery connected to the ignition circuit and to the dynamo-electric machine for supplying current to the dynamo-electric machine to operate the same as a motor, and to receive current from the

dynamo-electric machine operating as a generator; the connections being such that the battery supplies maximum current to the ignition circuit when operating the dynamo-electric machine as a motor, and the dynamo-electric machine supplies a constantly decreasing current to the ignition circuit when operating as a generator, as its speed is increased.

2. In an ignition system, the combination of a dynamo-electric machine having a commutator, main brushes, and an auxiliary brush between said main brushes; a shunt field connected to the main brushes of the dynamo-electric machine and an ignition circuit having one terminal connected to one of said main brushes and the other terminal connected to the auxiliary brush, the voltage of the machine between the auxiliary brush and that one of the main brushes to which the ignition is connected, tending to diminish with increase of machine speed.

3. In an ignition system, the combination of a dynamo-electric machine having main brushes and a third brush; a shunt field connected to the main brushes; ignition devices connected to the auxiliary brush and one of said main brushes, the voltage on the shunt field tending to increase with increase of machine speed, and the voltage on the ignition devices tending to decrease with increase of machine speed.

4. The combination of a dynamo-electric machine, having a field circuit; an ignition circuit; and means dependent on armature reaction for diminishing the voltage on the ignition circuit only as the machine speed is increased.

In testimony whereof, I affix my signature.

HENRY R. DAVIES
